UNITED STATES PATENT OFFICE.

DONALD H. McCORKLE, OF OAKLAND, CALIFORNIA, ASSIGNOR TO D. H. McCORKLE
MANUFACTURING CO., A CORPORATION OF CALIFORNIA.

BROODER STOVE.

Application filed September 17, 1924. Serial No. 732,176.

This invention relates to a brooder stove and its object is to provide means whereby a brooder house for young chickens may be heated to the correct temperature and maintained at that temperature until the chicks do not require artificial heat.

It will be understood by those skilled in the art that it is necessary to maintain a brooder house at a uniform temperature by some kind of an apparatus which will give the effect of a hen hovering her chicks, because it is natural for them to crowd together when night comes and if the heat is not properly diffused they will crowd up so closely as to kill the weaker chicks.

In addition to the danger of killing the weaker chicks, there is danger of "sweating" all of them if they crowd too closely. Such considerations as the above are of no particular moment where small numbers of chicks are raised, but where as many as 1800 chicks are raised, in one room, as with one of these stoves it will be seen that it is necessary to have almost perfectly natural conditions to raise a large percentage of the chicks.

Another object of the invention is to provide means whereby the brooder stove may be removed and a cover placed over the burner when artificial heat is no longer necessary.

It will be understood that any suitable type of burner or fuel may be used to accomplish the same results.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a vertical sectional view through the brooder stove and the floor of the brooder house,

Fig. 2 is a sectional view on a large scale of the corner of the burner drum,

Fig. 3 is a view in side elevation of the stove and floor of the brooder house showing the way the chicks collect around the stove when they go to sleep, and

Fig. 4 is a plan view of the stove, the dotted circles indicating the area in which the chicks collect when about 1800 are included in one batch.

The brooder house is ordinarily in such in-

stallations as the present about twelve to fourteen feet square and is made with well insulated tight walls to retain as much heat as possible.

The brooder floor indicated at 1, is supported by the joists 2, a hole being provided in the center of the room for the stove. The hole is circular and is provided with two channel iron supports 3 and 4 which are secured to the floor by bolts 5.

On these two beams the burner pan 6 is placed, said pan having its lower corner beaded at 7 and having a central opening to receive the draft tube 8. The draft tube 8 has a pan 9 riveted thereto by brackets 10, the object being to prevent pulses of air from blowing the flame out accidentally.

There is a hole in the burner drum bottom through which the gas pipe 11 is installed, said pipe having a plurality of burner tips 12.

The supply valve 13 and the thermostat 14 are both installed in the brooder room, the valve for convenience in operation and the thermostat for the purpose of regulating the room temperature by decreasing or increasing the fuel supply.

Inside the burner drum 6 there is a ring 15 of asbestos or other fire-proof insulating fibre which is held in place by a ring 16.

Slidable over the ring 6 is the cylindrical heater drum 17, the flat ring 18 secured to the floor filling up the space between the floor and said drum.

The hover consists of a flat circular sheet 18' of metal 18' which has a depending central flange 19 adapted to fit tightly over the top of the drum 17. Secured to the outer edges of the sheet 18 is a flat cone 20 which has an outlet pipe 21 connected to the chimney 22.

Within the cone and at a distance of several inches from the bottom 18' there is a flat sheet 23, rivets at its outer edges being used to secure it to the cone and it has notches 24 cut in it to allow the gases from the burner to pass to the chimney.

A short pipe 25 is secured in the cone and under the plate 23 to afford a hand hole to light the burner when desired, a tight cover 26 being provided to prevent the escape of gas into the room.

The cone also has two rings 27, 28 secured thereto to provide means to raise it out of the way when it is not in use.

It will be seen that the ring 17 frictionally engages the ring 6, and 19 frictionally engages the drum 17 so when the chicks do not require artificial heat the cone is raised to the roof to be out of the way of cleaning the house, the drum 17 is removed and the burner is covered over.

In operation the burner is started by lighting it through the hand hole extending 10 through the cone and the thermostat then operates to keep the room at the required temperature. Since the hot gas escaping is only that due to the combustion of the fuel, the heater is very economical, and as it 15 spreads the heat uniformly over a wide area the chicks go to sleep in a large ring as indicated in Figs. 3 and 4, spread out enough to prevent injury to the weaker ones.

Such heaters as this are from four to five 20 feet in diameter and they serve to heat a room for about 1800 chicks.

What I claim is as follows, but modifica-

tions may be made in carrying out the invention shown in the drawings and in the above particularly described form thereof 25 within the purview of the invention as defined by the annexed claim:

In a brooder stove, a burner, a pan having an open bottom within which the burner is installed, a thermostat to regulate the supply 30 of fuel to the burner, an insulating material around the edge of the burner pan, a heater drum detachably connected to said pan, a closed flat cone mounted upon the heater drum, a partition within the cone to cause 35 the uniform distribution of heat therefrom, a pipe for the escape of burned gas and a hand-hole pipe extending through the cone and partition therein to permit the burner to be lighted.

In testimony whereof I have hereunto set my hand this 12th day of September A. D. 1924.

DONALD H. McCORKLE.
